INTERLACING NEEDLE LOOM

Eric Lundgren, Braddock Heights, Md., assignor
to Thomas A. Unsworth, Burlington, Vt.

Application September 18, 1942, Serial No. 458,781

14 Claims. (Cl. 28—4)

This invention relates to an interlacing needle loom. More particularly, the invention pertains to a loom or the like for sewing, interlacing or needling a travelling layer of fibrous material to be made into batts or fabrics for use in resilient pads or cushions.

Machines now in use for the purposes indicated above are heavy, cumbersome and slow moving, being provided with elaborately machined sliding contact surfaces. In these conventional machines no provision has been made for conforming the movements of the interlacing needles with the movement of the fabric or batts being made. Further, conventional machines have to be made with substantial boards or racks to resist the pressures or pulls of interlacing needles. Conventional machines have also not been successfully applied to the interlacing or needling of batts or the like made from certain fibers which up to the present time have resisted all efforts to interlace or needle the same.

It is therefore an important object of the invention to provide a simple, rugged and inexpensive interlacing needle loom or the like capable of handling batts or fabrics made from any and all types of fibers.

Another important object of this invention is to provide a machine of the nature indicated wherein the movement of the interlacing needles is coordinated with the movement of the material being treated.

A further object of this invention is to provide a machine of the type indicated provided with opposed sets of needles whose pressures or pulls cancel each other so that little or no reaction results that would otherwise have to be taken care of by special machine elements.

Other and further objects and features of the invention will become apparent from the appended claims and from the following detailed description of an illustrative example of a loom according to this invention shown in the accompanying drawings, in which:

Figure 1 is a vertical cross sectional view of the loom taken along the line I—I of Figure 2, parts of the loom being broken away to show the loom construction more clearly;

Figure 2 is a vertical cross sectional view of the loom taken along the line II—II of Figure 1;

Figures 3 to 7 are greatly enlarged detail views showing the action of pulling needles;

Figure 8 is a greatly enlarged fragmentary side elevation of a pulling needle;

Figure 9 is a transverse cross sectional view taken along the line IX—IX of Figure 8;

Figure 10 is a greatly enlarged fragmentary side elevation of a pushing needle;

Figure 11 is a transverse cross sectional view taken along the line XI—XI of Figure 10;

Figure 12 is a greatly enlarged side elevational view of another type of pushing needle; and,

Figures 13 and 14 are greatly enlarged detail views showing the action of the pushing needles of Figures 10 to 12.

10 As shown on the drawings:

The machine indicated generally in Figures 1 and 2 with the reference numeral 10 is supported by a frame formed by members 11 consisting of structural shapes rolled from steel. This frame 15 can also be constructed from castings or any other material suitable for making a sufficiently substantial structure.

The moving parts of the machine include an upper crank shaft 12 and a lower crank shaft 13.

20 These two crank shafts are supported in bearings 14. The crank shafts 12 and 13 are rotated by gear reduction systems including a large gear 15 for the upper shaft 12 and a large gear 16 for the lower shaft 13.

25 The gears 15 and 16 are in turn driven, respectively, by pinions 17 and 18. The pinions 17 and 18 are attached, respectively, to shafts 19 and 20 journalled in corresponding bearings 21 and 22.

In a commercial machine the gears 15 and 16, the pinions 17 and 18, shafts 20, the bearings 21 and 22, as well as other essential moving parts would be enclosed in substantial metal housings containing a suitable oil for the continuous lubrication of the moving parts.

30 The shaft 20 is driven by a motor 10 and in turn drives the shaft 19 synchronously through a sprocket chain 71 and sprocket wheels 72 and 73 affixed, respectively, to the shafts 20 and 19.

35 Sprocket wheels 74 keep the chain 71 taut. It is possible to effect driving otherwise, as by gears and shafts, synchronous motors or any other suitable means.

At each end the shafts 12 and 13 are provided, respectively, with cranks or crank disks 23 and 24.

40 Each one of the crank disks 23 and 24 is provided with suitable means for attaching a crank pin 25. For example, T-shaped slots 26 may be milled into all the crank disks 23 and 24. The bases of the crank pins 25 fit into the T-shaped slots 26, the pins 25 being so designed with suitable bearings and sleeves that the pins may be clamped securely in the slots while retaining an easy working joint for connection between the crank pins 25 and connecting rods 27.

45 A number of conventional constructions are available for

50 connecting the pins 25 to the connecting rods 27.

55 Figures 1 and 2 show the upper and lower crank disks 23 and 24 respectively, each having a central

this purpose. The object of the slotted design is to provide for adjustment of the stroke of the machine by moving the pins 25 in the slots 26. Moving the pins away from the center produces a longer stroke, while movement in the opposite direction produces a shorter stroke. In place of the slot construction, the crank disks can have a number of holes drilled at varying distances from the center of the disks, when adjustment of the stroke can be had by moving the crank pins 25 into a hole located so as to produce the desired stroke. In the construction shown in the drawings, means for adjusting the position of the pin in the slot can include, for instance, a screw located in the slot 26 passing through a tapped hole in the base of the crank pins 26 whereby the stroke may be adjusted simply by turning such screws.

The shafts 12 and 13 are provided with counter balances 28 disposed to balance effectively the weight of the crank pins 26, connecting rods 27 and any other weights attached to the connecting rods 27 as explained hereinbelow. For extraordinarily high speeds, it may be essential to employ two counterbalances in place of each of the counterweights 28 shown in Figure 1, these two counterweights being disposed as nearly opposite the crank pins as possible to avoid lack of both static and dynamic balance. In the drawings, the counterweights as shown as clamped by screws 39 to rods 29 extending from the shafts 12 and 13, although obviously other attaching means may also be employed.

Attached to the connecting rods 27 are extension connecting rods 31 so arranged as to form with the connecting rods 27 units that can be shortened and lengthened. For this purpose, the connecting rods 27 and 31 may be slotted lengthwise and clamped together by bolts 32.

At the lower ends of the upper connecting rods 31 a beam 33 is securely attached, while another beam 34 is attached to the upper ends of the lower connecting rod 31. The beams 33 and 34 are provided with suitable means for holding needles 35.

The extension connecting rods 31 are also slotted at 36 to fit over bolts 37 so disposed that the bolts can be clamped in any position along the length of the slots. On the ends of the bolts 37 are provided contactors 38 adjusted to keep the beams 33 and 34 from moving longitudinally, by restraining the beams between vertical frame members 11. To the bolts 37 are also attached restraining rods 39 to which in turn are attached secondary restraining rods 40, both the rods 39 and 40 being formed with matching longitudinal slots and with bolts 41 so that the rod unit formed by the members 39 and 40 can be lengthened or shortened as desired by moving the members 39 and 40 relative to each other and then clamping the members in the desired position by means of the bolts 41. As shown in Figure 2, the right-hand ends of each connecting rods 39 and 40 is restrained by a pivot 42 which is adjustable vertically in a slot 43 formed in a plate 44 movable horizontally and held to the frame members 11 by bolts 45 passing through slots 46 in the plates 44.

A fibrous batt or fabric A to be interlaced or needled may be produced by garnetting and lapping, garnetting only, picking and blowing, manual distribution, or otherwise. Such a batt is brought to the machine 10 by a conveyor apron 47 moving on a roller 48 driven by a shaft 49. A similar arrangement is provided for the other end

of the apron. As the batt A at this stage usually is characterized by great volume and low density, the batt may be squeezed by a roller 50 to facilitate its entry between an upper rack 51 and a lower rack 52. The racks 51 and 52 are so constructed as to interpose a substantial member between each pair of adjacent needles 35, these members being preferably constructed of steel, although other materials also are suitable. As shown in Figures 1 and 2, the racks 51 and 52 may include transversely disposed channel sections 51a and 52a having attached thereto pluralities of steel bars 51b and 52b extending in the direction of travel of the batt A. The bars 51b and 52b are bent to provide therebetween a tapered entrance for facilitating the entry of the batt or fabric to be needled or interlaced. The spacing of the bars 51b and 52b is the same as that of the needles 35, being such that the needles 35 are free to move upwards and downwards without interference by the bars 51b and 52b. The channels 51a and 52a are located in the machine frame and attached thereto in such a manner that the channels can be raised or lowered and tilted at varying angles, being held in adjustment by brackets 53 and 54 which are provided with slots and bolts.

Under certain conditions and to effect certain results, it is necessary to change the moisture or other fluid conditions of the batt A. For this purpose, I have provided nozzles 55 and 56 which may be used to spray the batt A before introduction into the machine 10 with steam, fine water spray, oils, aqueous solutions or dispersions, gases or vapors, as may be required to obtain the desired product.

The needled batt is supported by a plate 78.

The finished product is removed from the machine by means of draw rollers 57 and 58. The rollers 48, 50, 57 and 58 may be provided, respectively, with sprockets 48a, 50a, 57a and 58a, over which passes a sprocket chain 59 kept taut by sprocket wheels 60 and 61 journaled from the machine frame. The relative speeds of the rollers 48, 50, 57 and 58 can be changed by changing sprockets on the various shafts, thus affecting the nature of the finished product. If the rollers 57 and 58 are set to move at a speed greater than that produced by the advancing movement of the needles 35, there will be a greater distance between the needle strokes than if the rollers were set to move at the same speed as that of the advancing movement, as the batt will move forward during the period when the needles are not engaged therein (see Figure 5). Other arrangements for changing the speed ratios can also be made such as variable speed friction drives, variable speed motors and engines, and the like. The entire train of feed rolls and draw off rolls is also arranged so that its speed may be regulated according to the speed of the machine producing the batt treated in the present machine.

It has been found that when the machine is used on certain types of fibers, there is a tendency for some fibers to fall through the racks 51 and 52 and accumulate around the lower needles 35. To take care of such accumulation the machine is provided with a set of auxiliary needles 65 which work approximately at right angles to the needles 35. The auxiliary needles 65 shown in Figure 2 are of "fish tail" construction, although hooked needles may be used to pull the fibers from between the needles 35 instead of pushing the fibers off as shown in the drawings. The needles

65 are fastened to a needle board 66 which is in turn carried by levers 67 attached to each end of the needle board 66. These levers are pivoted at 5 68 in vertical frame members 11 and are driven by connecting rods 69 adjustably attached to the lower main connecting rods 27 and 31. The levers 69 are so arranged and adjusted that when the lower main connecting rods descend, the needle board 66 with its needles 65 will move forward and push off any fibers which have lodged among the needles 35. During the upward stroke of the 10 lower main connecting rods 27 and 31, the needle board 66 is retracted out of the way of the ascending needle bar 34. The needles 65 are so spaced and arranged that they move between the needles 35 without touching the latter or interfering with their movement. With most type of needles it is only necessary to allow the upper needles 35 to descend below the level of the lower rack 52, where the needles will hook any fibres which have lodged among the lower needles 35 and insert the hooked fibres into the batt.

The machine functions as follows. Shafts 12 and 13 rotate as indicated by the arrows in Figure 2. Rotation causes the needles 35 to ascend and descend and withdraw from contact with the batt A as the upper crank pin 25 ascends and the lower crank pin 25 descends. See Figures 3 to 5. During that part of the revolution illustrated in Figure 5, the needles 35 are disengaged from contact with the batt, and it can be seen that the points of the needles move in a direction opposite to the direction of movement of the material being needled. More particularly, the upper needle points move against the direction of batt travel during the last half of their ascending movement, and during the first half of their descending movement and in the direction of batt travel during the second half of their descending movement and the first half of their ascending movement. 40 The converse is true of the lower needle points. When the upper needles have completed the first half of their descending movement, the descending needles again enter the batt. During the following portion of the stroke, the needle points will move forward in the direction of travel of the batt and will approximately match the speed of the batt. The top of the stroke is shown in Figure 3. After the top of the stroke (or the bottom of the stroke in case of the lower crank), the points of the needles will be retracted through the batt while still moving in the direction of batt travel. The hooked needle points will then catch and pull up fibrous material, as illustrated in Figure 4. When the second half of the ascending movement is initiated, the needle points will commence to move in a direction opposite to the direction of batt movement. The hooks of the needle points being placed on the side of the needles leading in the direction of batt travel, the hooks will now disengage the fibers picked up as the needles were pulled back through the batt. The needles will then repeat the above described cycle.

The extent of travel of the needles lengthwise of the batt is determined by the location of the bolts or fulcrum pins 37. The closer the pins are to their respective crank pins 25, the larger will be the extent of travel. The travel is also dependent upon the stroke. For a given location of the fulcrum 37, a longer stroke will cause a greater extent of travel. However, when a long stroke is used, the extent of travel can be reduced by moving the fulcrum 37 away from the eccentric or crank pin 25. The machine can thus be adjusted to produce a very wide range of stroke and 75

travel combinations. As will be seen, with proper adjustment of the speeds of the feed rolls and conveyor, the draw off rolls, and the stroke and travel of the needles, practically any type of pad can be made, with few or many tufts per unit of surface area. The design of the needle hooks will also influence the nature of the finished product. A large hook will produce a large and stiff fibrous tuft.

10 It is also possible to raise or lower a set of needles 35 to operate at various levels relative to the racks 51 and 52. If, as shown in Figure 7, the racks are brought closely together and one set of needles is made to pull out a considerable distance above the batt, while the other set of needles pulls out close to the rack, it will be found that the side first mentioned will be soft and fluffy, while the other side will be hard and firm. The advantage of such interlacing is readily apparent in the case of material produced for use in mattresses and furniture upholstery. Figure 7 also illustrates the use of two different types of fibres in the same batt. A softer fibre is placed on the bottom and a strong and firm fibre on top. As shown, the firm fibre is pulled down by the lower needles to form a firm back for the batt while the lighter and softer fibre is pulled up by the upper needles to form a soft surface. Figure 6 shows a batt with less pronounced fluffiness.

for advancing said batt between said sets of needles to be needled thereby, connecting rods for effecting a reciprocal movement of said needles to cause said needles to be inserted into said batt and to be withdrawn therefrom, and for each connecting rod a restraining arm having one end pivotally attached to said connecting rod and another end pivoted at its fixed point to said machine, said restraining arm being operative to guide the reciprocal movement so that said needles when inserted into said batt move in the direction of advancement of said batt.

3. A machine for needling a batt of fibrous material including two spaced beams, needles on the opposed sides of said two beams, means for advancing said batt between said needles to be needled by said needles, rods pivotally attached to the ends of said beams, means for reciprocally moving said rods to cause said needles to be successively inserted into said batt and to be withdrawn therefrom, and for each rod a restraining arm having one end pivotally attached to a fixed point on said machine and another end pivotally attached to said rod intermediate the ends of said rod, said restraining arms being operative to guide the reciprocal movement of said needles when inserted into said batt to move the needles in the direction of advancement of said batt.

4. A machine for needling a batt of fibrous material including two spaced beams, needles on the opposed sides of said two beams, means for advancing said batt between said two beams to be needled by said needles, two crank shafts, means for rotating said crank shafts in opposite directions, cranking means on said shafts, connecting rods driven by said cranking means for reciprocally moving said beams to cause said needles to be inserted into and to be withdrawn from said batt, and for each connecting rod a restraining arm having one end pivotally attached to a fixed point on said machine and another end pivotally attached to said connecting rod intermediate the ends of said rod, said restraining arms being operative to guide the reciprocal movement of said needles when inserted into said batt to move the needles lengthwise of said batt in the direction of advancement thereof.

5. A machine for needling a batt of fibrous material including two spaced beams, needles on the opposed sides of said beams, means for advancing said batt between said beams and transversely thereof to be needled by said needles, two crank shafts, means for rotating said crank shafts in opposite directions, two radially slotted crank disks on each crank shaft, a crank pin in the radial slot of each crank disk, means for securing said crank pin in said slots at an adjusted distance from the center of the crank disks, a telescopic connecting rod pivotally connected to each crank pin and to each end of said beam, means for locking said connecting rods in any telescoped position, a telescopic restraining arm for each connecting rod having at one end a pivotal connection to said machine and at another end a pivotal connection to said connecting rod, means for adjustably securing said pivotal machine connection to said machine, means for adjustably securing said pivotal connecting rod connection to said connecting rod intermediate the ends thereof, means for locking said restraining rod in any telescoped position, said connecting arms and restraining arms jointly being operative to move said needles into and out of said mass and in the direction of travel of said batt while the needles are inserted therein, and spaced racks extending parallel with said beam having spaced bars extending between said beams and said needles for supporting said batt while the batt is needled.

6. A machine for needling a batt of fibrous material including two spaced beams, needles on the opposed sides of said beams, means for advancing said batt between said beams and transversely thereof to be needled by said needles, two crank shafts, means for rotating said crank shafts in opposite directions, two radially slotted crank disks on each crank shaft, a crank pin in the radial slot of each crank disk, means for securing said crank pin in said slots at an adjusted distance from the center of the crank disks, a telescopic connecting rod pivotally connected to each crank pin and to each end of said beam, means for locking said connecting rods in any telescoped position, a telescopic restraining arm for each connecting rod having at one end a pivotal connection to said machine and at another end a pivotal connection to said connecting rod, means for adjustably securing said pivotal machine connection to said machine, means for adjustably securing said pivotal connecting rod connection to said connecting rod intermediate the ends thereof, means for locking said restraining rod in any telescoped position, a telescopic restraining arm for each connecting rod having at one end a pivotal connection to said machine and at another end a pivotal connection to said connecting rod, means for adjustably securing said pivotal machine connection to said machine, means for adjustably securing said pivotal connecting rod connection to said connecting rod intermediate the ends thereof, means for locking said restraining rod in any telescoped position, a telescopic restraining arm for each connecting rod having at one end a pivotal connection to said machine and at another end a pivotal connection to said connecting rod, means for adjustably securing said pivotal machine connection to said machine, means for adjustably securing said pivotal connecting rod connection to said connecting rod intermediate the ends thereof, means for locking said restraining rod in any telescoped position, said connecting arms and restraining arms jointly being operative to move said needles into and out of said mass and in the direction of travel of said batt while the needles are inserted therein, a third beam, needles on said third beam extending transversely between the lower set of needles attached to said first two beams, a pivot rod attached to each end of said third beam having one end pivotally attached to said machine, a connecting rod for each pivot rod pivotally attached at one end to said pivot rod and having at the other end a pivot connection to a connecting rod operative to move the lower of said first two beams, means for adjustably securing said last mentioned pivot connection to said last mentioned connecting rod intermediate the ends thereof, and spaced racks extending parallel with said beam having spaced bars extending between said beams and said needles for supporting said batt while the batt is needled.

7. A device for needling a traveling fibrous batt including opposed sets of needles disposed so that said batt will advance therebetween, crank rod means for reciprocally moving said needles to have the needles of the sets simultaneously inserted into and then withdrawn from the batt, and restraining arms pivotally attached to said device and to said rods intermediate the ends of the latter for effecting movement of said needles in the direction of travel of said batt when said needles are inserted in said batt.

8. A device for needling a traveling fibrous batt including opposed sets of hooked needles disposed so that said batt will advance therebetween, the hooks of said needles being turned in the direction of advancement of the batt, crank rod means for reciprocally moving said needles to have the needles of the sets simultaneously inserted into and then withdrawn from the batt, and restraining arms pivotally attached at one end to said machine and pivotally attached at the other end to said rod intermediate the ends thereof for defining a fulcrum point intermediate the ends of said rod whereby said needles when inserted and when being withdrawn from the batt will move in the direction of travel of the batt and when com-

pletely withdrawn from the batt will move in a direction opposite to the direction of travel of the batt so that said hooks will be disengaged from fibrous batt material.

9. An interlacing or needling machine for treating fibrous pads including two generally parallel crank shafts disposed one above the other, two crank disks on each crank shaft, a connecting rod for each crank disk, transverse members extending between the connecting rods driven from each crank shaft, needles on the opposed sides of said transverse members, restraining arms pivotally connected to said connecting rods intermediate the ends thereof and pivotally connected to said machine for defining a fulcrum on said connecting rods, feed rollers ahead of said needles and draw off rollers behind said needles for advancing a fibrous batt between said needles, said crank shaft-crank-connecting rod-restraining arm system being so arranged as to produce a reciprocal needle movement into and out of said batt, the movement of the needles of said two transverse members being synchronized, and all the needles moving along with said batt while inserted therein.

10. An interlacing or needling machine for treating a continuously traveling fibrous batt including opposed sets of needles, means for effecting a reciprocal movement of said sets to and from each other to insert said needles into said batt and to retract the needles therefrom, and means for tilting said needles during said reciprocal movement so as to effect a sideway movement of the points of said sets of needles in the direction of travel of said batt when the needle points are within said batt.

11. An interlacing or needling machine for treating a traveling fibrous batt including opposed sets of needles, supporting means for said batt including spaced racks disposed above and below of said batt ahead of said needles and having spaced bars extending cantileverwise between said needles in the direction of travel of said batt, means for effecting reciprocal movement of said

sets to and from each other, and means for guiding said reciprocal movement so as also to effect a sideway movement of said sets of needles in the direction of travel of said batt when said needles are in a more closely approximated relationship.

12. An interlacing or needling machine for treating a traveling fibrous batt including opposed sets of needles, means for effecting reciprocal movement of said sets to and from each other, means for guiding the reciprocal movement so as also to effect a sideway movement of said sets of needles in the direction of travel of said batt when the needles are in a more closely approximated relationship, an auxiliary set of needles disposed so as to be movable between and transversely of the individual members of said opposed sets of needles to remove fibres lodged between said opposed sets of needles and means for moving said auxiliary set of needles transversely of said opposed sets of needles.

13. An interlacing or needling machine for treating a traveling fibrous batt including opposed sets of needles, means for effecting a reciprocal movement of said sets to and from each other, means for guiding said reciprocal movement so as also to effect a sideway movement of said sets of needles in the direction of travel of said batt when the needles are in a more closely approximated relationship, and means disposed ahead of said needles for introducing a lubricant into said batt.

14. An interlacing or needling machine for treating a continuously traveling fibrous batt including a set of needles, crank means for effecting reciprocal movement of said set of needles into and out of said batt, and means providing a fulcrum for said set of needles intermediate the ends thereof for tilting said needles in the direction of travel of said batt when the needles are within the batt and in the opposite direction when the needles are outside said batt.
